UNITED STATES PATENT OFFICE.

OSCAR S. TEALE, OF BLOOMFIELD, NEW JERSEY, ASSIGNOR TO GEORGE H. WILEY,
OF NEW YORK, N. Y.

RETOUCHING-MACHINE.

1,386,909.

Specification of Letters Patent. Patented Aug. 9, 1921.

Application filed November 26, 1919. Serial No. 340,764.

To whom it may concern:

Be it known that I, OSCAR S. TEALE, a citizen of the United States of America, and a resident of the city of Bloomfield, county 5 of Essex, State of New Jersey, have invented certain new and useful Improvements in Retouching-Machines, of which the following is a specification.

This invention relates to hand controlled 10 and power driven instruments for retouching photographs and negatives, prints and pictures, etc.

The instrument comprises a casing, preferably cylindrical, adapted to be manually 15 operated; a two part device shaft longitudinally adjustable, one section of which extends through the upper end of the casing and is adapted to be connected to a suitable source of power; a pencil or stylus carrying 20 shaft extending beyond the lower end of the casing and provided with a universal journal working in a bearing fixedly held in the casing; a bearing in the upper part of the casing in which the outer section of the drive 25 shaft is fitted to rotate without end or axial play; a bearing similarly controlling the inner section of said shaft and fitted in the casing so as to slide axially therein; means for adjusting this bearing and means connecting the adjacent ends of the lower section 30 of the drive shaft and of the pencil carrying shaft; whereby the pencil shaft may be set and held in axial position, so as to rotate directly with the drive shaft and set in 35 different angular positions to the axis of the drive shaft, causing its ends to revolve around the axis with the universal bearing as an immovable center.

An essential feature of the invention, to 40 insure accuracy and freedom of action of the working parts, is that all of main bearings in the casing are coaxial. Other novel features reside in the special construction of the various devices, especially the pencil 45 shaft controlling means and the bearings; all of which will now be fully described by reference had to the accompanying drawings, in which:

Figure 1 is a longitudinal section of a re- 50 touching instrument embodying the features of this invention.

Fig. 2 is a view taken at right angles to Fig. 1, showing the central position of the instrument with the casing removed.

Figs. 3, 4 and 5 are transverse sectional views on the lines 3—3, 4—4 and 5—5, Fig. 1, respectively.

The casing consists of a central part 6, an upper cap 7, and a lower conical section 8, the adjacent ends of the three parts being internally screw-threaded. The shell 9, of the upper bearing screws into the thread of the top of the part 6, and the cap 7, screws over the upper half of said shell 9; similarly the lower universal bearing 10, is screwed into the lower end of the part 6, and the conical section 8 is screwed over the part of said bearing projecting beyond the end of part 6; thus the parts 9 and 10 of the upper and lower bearings constitute parts of the casing, whereby the three sections 6, 7 and 8 are rigidly held together.

The upper section 11 of the drive shaft, to which a source of power may be connected by a flexible shaft in the usual manner, is formed with a circumferential groove 12, preferably concaved, into which fits a bearing ring, 13, diametrically divided and formed to seat in the shell 9, and held firmly in position by screws 14. Said shaft while free to rotate is held longitudinally stationary. The journal of the lower section 15, consists of opposed conical faces 16, which seat in corresponding bearing faces in the divided bearing 17, which is firmly held in the shell 18 by screws 19. This bearing is controlled and axially adjusted by being connected to the manipulating sleeve 20, by bars 21, secured at their upper ends to the shell 18, by the screws 19, and attached to the sleeve 20, by their rectangular hands 22 at their ends which pass through slots in the casing and into holes in said sleeve. In an axial socket 23 at the top of section 15, fits the inner end of section 11, of the drive shaft, said inner end being provided with a key or feather 24 fitted to slide in a slot formed in one side of the socket, whereby the two sections of the shaft are carried to rotate together under all axial adjustments.

The universal bearing 10, is longitudinally divided, the two parts being held together at the upper ends by a ring 23, secured thereto by screws. The lower part of the bearing is tapered, corresponding to the taper of the lower section 8 of the casing, which by seating on the taper part of said bearing, when the bearing and the sections of the cas-

ing are assembled, also assists in holding the two halves of the bearing together. This bearing has a central spherical cavity 24, in which works the spherical journal 25, rigidly secured to or forming part of the pencil carrying shaft 26, which is hollow for the reception of the pencil or stylus and is provided at its lower end with an ordinary clamping chuck 27.

10 The adjustable means for imparting motion from the shaft 15, to the shaft 26, from a simple rotary motion, when the axis of said shaft 26, is coincident with the axis of the main bearings, to increasing circular movements of the axis of shaft 26, around said main axis, with a stationary point at the center of the universal bearing, consists of a hollow head 28, at the lower end of shaft 15, having inclined slots 29, in the opposed walls, and a crosshead or lugs 30 projecting from the flattened end of the solid part 31 of the shaft 26; the arrangement being such that, the crosshead 30 fitting in the slots 29, the shaft 15 with its head 28, may by means 25 of the sleeve 20 and its associated devices be set to locate the axis of shaft 26 coincidentally with the main axis of the instrument or moved into angular positions relatively thereto, so that as said head rotates the upper end of the axis of shaft 26, will move in circles of varying dimensions and the point of the pencil or stylus be carried to correspondingly inscribe or mark circles by moving in the opposite direction. Holding the 30 instrument stationary over the photograph or other object to be retouched circular markings of various sizes may be produced; if the instrument be moved over the object overlapping circular or scroll like markings 35 will result.

It is evident that the instrument may be used in dot and straight line retouching work, as an ordinary pencil or stylus, by setting the shaft 26, on the axis of the bearings. 40 The point of the pencil or stylus will of course rotate if the source of power is not cut off, but such movement need not militate against handling of the stylus for line or dot work.

45 I claim:

1. A retouching instrument, comprising a casing, a drive shaft extending from and having bearings at one end of the casing, a pencil or stylus carrying shaft extending from the other end of the casing and provided with a universal journal, a bearing for said journal fixedly held in the casing coaxially with the drive shaft bearings, a radially adjustable connection between the adjacent ends of the shafts, a sleeve slidable on the casing near its stylus carrying end, and bars extending lengthwise the casing and

connecting said sleeve with the inner bearing of the drive shaft.

2. A retouching instrument, comprising a 65 casing consisting of a central section, a cap at one end, similarly internally screw threaded, a bearing shell fitted in the central section, as a bushing to hold them together and a conical end section secured to the other 70 end of the central section, a drive shaft extending from and having bearings at one end of the casing, one of said bearings being held in the shell connecting the central section and cap, a pencil or stylus carrying 75 shaft extending from the other end of the casing and an adjustable connection between the drive shaft and pencil carrying shaft.

3. A retouching instrument, comprising a casing consisting of a central section, a 80 cap at one end, similarly internally screw threaded, a bearing shell fitted in the central section, as a bushing to hold them together and a conical end section secured to the other end of the central section by a peripherally screw threaded bearing seated in them, a drive shaft extending from and having bearings at one end of the casing, one of said bearing being held in the shell connecting the central section and cap, a pencil or stylus carrying shaft extending from the other end of the casing and provided with a universal journal working in said bearing and an adjustable connection between the drive shaft and pencil carrying 95 shaft.

4. A retouching instrument, comprising a casing, a drive shaft extending from and having bearings at one end of the casing, said bearings which are formed to avoid end 100 play on the shaft being diametrically divided securely held in sleeves seated in the casing, a pencil or stylus carrying shaft extending from the other end of the casing and provided with a universal journal, a bearing 105 for said journal fixedly held in the casing coaxially with the drive shaft bearings, a radially adjustable connection between the adjacent ends of the shafts and means for setting said connection.

5. A retouching instrument, comprising a casing, a drive shaft extending from and having bearings at one end of the casing, a pencil or stylus carrying shaft extending from the other end of the casing and provided with a universal journal, a bearing for 115 said journal longitudinally divided, a ring secured to the upper ends of the two parts of the bearing which are also fixedly held in the casing coaxially with the drive shaft 120 bearings, a radially adjustable connection between the adjacent ends of the shafts and means for setting said connection.

OSCAR S. TEALE.
